PLUGGABLE REED RELAY PACKAGE

Lyndon A. Depew, Endicott, N.Y., assignor to International Business Machines Corporation, New York, N.Y., a corporation of New York

Filed Apr. 1, 1963, Ser. No. 269,606

8 Claims. (Cl. 200—87)

This invention relates to the packaging of dry reed switches, and more particularly to a pluggable reed relay mounted on a printed circuit card or the like.

As is well known, the dry reed switch basically comprises two overlapping magnetic cantilever beams surrounded by a dry inert gas and sealed in a glass envelope. Upon the application of a magnetic field supplied for instance by energizing coils or permanent magnets, the reeds are attracted together to close the switch.

An object of the invention is to provide a generally improved and more satisfactory dry reed switch package having the features of economical production and assembly, and convenient servicing and testing.

Another object is the provision of a new and improved reed relay package which can be made readily in various sizes to accommodate one or more normally closed or normally open reed switches and the required field producing device or devices.

Yet another object is to provide a new and improved pluggable reed relay package for printed circuit cards designed so that assembling the package to the cards achieves the dual purpose of mechanical and electrical connection.

The foregoing and other objects, features and advantages of the invention will be apparent from the following more particular description of a preferred embodiment of the invention, as illustrated in the accompanying drawing, wherein:

FIG. 1 is a partially exploded perspective view, partly diagrammatic, of the reed relay package according to the invention mounted on a printed circuit card; and

FIG. 2 is a partial plan view of the assembled reed relay package showing a modified end plug, the end plug being illustrated withdrawn in dotted lines.

The printed circuit board reed relay shown in the drawing includes a maximum of four dry reed switches, although it will be understood that a similar package may be made in different sizes to accommodate one to six or more reed switches. Each of the reed switches comprises two reeds 11 and 13 of magnetic material supported as overlapping cantilevers and hermetically sealed inside a glass envelope 15. The glass sealing envelope 15 frees the overlapping contact ends from external environmental effects and also encloses the most favorable gaseous environment, such as dry nitrogen, for the operation of the contacts. The reeds have at either end coaxial wire-like shanks or leads 17 external to the glass seal 19. For further information on the construction and operation of a reed switch, see for example U.S. Patent 2,289,830 to W. B. Ellwood dated July 14, 1942. A particular reed switch which may be used is that described in the co-pending application S.N. 229,457 of P. R. Schulz filed October 9, 1962, and entitled "Reed Switch Manufacture," which is assigned to the same assignee as the present invention.

The reed switches are contained side by side in a single layer within a hollowed-out bobbin 21 having a central hub 23 and integral end blocks or flanges 25 and 27. The bobbin 21 is made of an insulating material such as a suitable plastic having the proper characteristics for this use. The hub 23 has a flattened oval cross-section of a size such that the four reed switches can be easily inserted from either end without undue play.

A pair of energizing coils 29 and 31 are wound around the external surface of the hub 23 retained by the opposing surfaces of the end blocks 25 and 27. It is understood that FIG. 1 diagrammatically illustrates the coils, and that in actual practice the coils have many turns and build up to a thickness and terminate just short of the end blocks. Although it is possible to use only one energizing coil to operate the reed switches, it is more economical to use two coils, the first of which operates initially to provide the relatively strong magnetic field needed to close the reed contact ends and which remains on until the second coil is energized to provide the relatively weak magnetic field needed to keep the contacts closed, once they are initially brought into contact or "picked." To provide the necessary electrical isolation from one reed relay package to the next when mounted in proximity, magnetic shielding tape 32 is wound around the hub 23 over the coils 29 and 31. Each end of the coils 29 and 31 is wrapped around one of the four coil terminal lugs 33 and soldered to provide good electrical connection.

The terminal lugs 33 are mounted at the ends of the elongated end blocks 25 and 27 in the portions projecting laterally beyond the edges of the hub 23. The extremities of each end block have vertical bores 35 which, for convenience of molding of the bobbin 21, have approximately a square cross-section. Transverse to the axis of each bore 35 is a slot 37 which extends approximately mid-way into the bore at a point about a little more than half-way down the height of the end block. At right angles to the slot 37 and above it, approximately parallel to the inner side wall of the bore 35, is another slot 39. The two slots 37 and 39 together suggest a T-shape.

Before assembly, the coil terminal lug 33 is L-shaped and comprises an elongated flat terminal end from which projects a wire-like contact 41. The terminal lug 33 is adapted to be inserted automatically into the slots 37 and 39 from the side, the contact 41 grounding against the ends of the slot 37. The flattened terminal end extends upwardly in the slot 39 and is frictionally held in place by the rounded projection 43. An end of one of the coils 29 or 31 is attached to its respective terminal lug 33 by inserting the end sideways into the inner end of the slot 37 and then upwardly through the slot 39 and is wrapped several times around the end of the lug in that portion having opposing recesses in its edges to better secure the winding. After securing all four coil ends in this manner, the wrapped terminal ends are dip soldered and turned down through about 90° into the recesses 45 in the end blocks.

In order to provide electrical connection with the wire-like contacts 41 of the terminal lugs 33, opposing pairs of bifurcated connectors 47 are mounted upstanding from a printed circuit card 49 or the like on which the reed relay package is pluggable. The connectors 47 which are illustrated are stamped out connectors attached to the card 49 by a bead 51 at one side and is nipped off to secure the connector at the other side (not here shown). On the other side of the card 49, likewise not here shown, the connectors 47 make connection to printed circuit line or land patterns and are preferably soldered. The upper end of the connector 47 has an inwardly tapering tubular configuration terminating in outwardly flaring lips 53 providing an opening which connects with opposing slots 55. Upon plugging the package onto the card 49, the contacts 41 of the terminal lugs are engaged by the flaring lips 53 and slide downwardly into the opposing slots 55 as is illustrated in dotted lines to become securely wedged in place and provide good electrical contact forces.

The central portion of each of the end blocks 25 and 27, between the walls providing one surface of the bores 35, is hollowed out to provide a rectangular opening 57 which connects with the opening inside of the hub 23.

For clarification as to this detail, see the article "Pluggable Reed Relay Package" by the inventor, published in the April 1962 issue (Volume 4, No. 11) of the IBM Technical Disclosure Bulletin, which discloses essentially the same reed relay package as is herein described. Each end block has four vertically aligned pairs of approximately square apertures 59 between the bores 35 at either end and in connection with the rectangular openings 57. It will be noted that the leads or shanks 17 of the reed switches extend into the opening 57 at each side and that the leads are trimmed equally at either side so that the total length of the reed switch with trimmed leads is approximately the same as the length of the bobbin 21.

An end plug 61 is inserted into the hollowed-out bobbin 21 at one side to mechanically position the reed switches and to facilitate electrical connection in the manner to be explained. An identical end plug 63 is inserted into the bobbin opening at the other side for a similar purpose. The end plugs are made of a suitable insulating material such as a plastic and are preferably made of the same material as the bobbin 21. The end plug 63 comprises a rectangular body portion 65 which is adapted to be slidably received in the rectangular opening 57 and has four vertical bores 67 of approximately square cross-section spaced to be in alignment with the pairs of apertures 59 when the end plug is inserted into the bobbin. Projecting inwardly from the body portion 65 are three posts 69 having concave side edges to receive a portion of the glass envelope 15 of a reed switch. The ends of the posts are tapered to facilitate insertion of the reed switches between the posts. Of course, the two outer reed switches are cradled between one concave post edge and the curved inside of the bobbin 23. Between the post 69 and to either side are concave sockets or seats 71 for receiving the ends of the glass envelopes 15, the rim 73 formed by the outer edges of the concave sockets 71 and the posts 69 being of the same shape as the opening in the hub 23 to fit therein. The lead 17 of each reed switch is received in aligned holes 75 extending from the bottom of the concave socket 71 axially through the spaced walls of the body portion 65.

The modified end plug 61' shown in FIG. 2 is identical to the corresponding part of FIG. 1 but has the addition of a flange 77 to facilitate removal of the end plug from the bobbin.

A normally closed reed switch is obtained by placing a permanent magnet 79 adjacent the glass envelope 15 to create a magnetic force which closes the contact ends of the reeds 11 and 13. In the assembled package, the permanent magnet bar 79 is retained between the ends of opposing posts 69 and the sides of adjacent glass envelopes 15. Of course, when a normally opened switch is desired, the permanent magnet 79 is omitted. A polarization peg 81 is provided on the bottom of the bobbin 21 which fits into a hole 83 in the printed circuit card 49 when the pluggable assembly comprising the assembled reed switches, bobbin and end plugs with or without the permanent magnet is mounted on the card or support 49. Of course, normally the coils 29 and 31 are wound on the bobbin 21 before making this assembly.

In assembling the reed relay package using either the end plug of FIG. 1 or the modified end plug of FIG. 2, the four reed switches are inserted onto one of the end plugs 61 or 63 with the ends of the glass envelopes 15 received in the concave sockets 71 and the leads 17 extending through the aligned axial holes 75 in the body portion 65. If the permanent magnets 79 are to be used, two such magnets are placed against the ends of the outer posts 69 retained between the glass envelopes of the adjacent reed switches. The end plug with the assembled reed switches and magnets is now inserted into an opening at one end of the bobbin and pushed into place until seating in the end block 25 or 27 with the bores 67 in alignment with the spaced apertures 59 to provide continuous vertical bores through the assembly. The other end plug may now be inserted into the other

end of the bobbin and adjusted until the leads 17 at the other ends of the reed switches enter the holes 75. It is seen that the end plugs 61 and 63 mechanically support the reed switch leads 17 at spaced points at either side of the vertical bores in the assembly and there is no misalignment or bending of the leads as the pluggable assembly is inserted down onto the connectors 47 on the printed circuit card 49. There are a pair of connectors 47 for each of the reed switches and two additional pairs for the coil terminal lugs 33 arranged in two rows on the card 49. When the reed relay package is assembled to the printed circuit card 49, the connectors 47 extend upwardly into the vertical bores provided by the aligned end block apertures 59 and end plug bores 67 to provide mechanical fastening of the end plugs to the bobbin 21. At the same time electrical connection is established through the reed switches as the leads 17 become wedged in the bifurcated connector slots 55. It can now be seen that the reed switch leads 17 and the terminal lug contacts 41 desirably present the same mating shape to the connectors 47. Although illustrated as wire-like, the contacts 41 may be blade shaped with a rounded bottom edge, since this type of contact has the same mating shape as the leads 17.

The advantages of the pluggable reed relay package according to the invention will be reviewed and enumerated. Pluggability provides for quick and convenient assembly of the relay to the card, and servicing and replacing of the entire reed relay are likewise quick and convenient. The ability to disassemble and reassemble easily provides for economical replacing of individual reed switches. By their design, the end plugs 61 and 63 provide for positioning of the reed switches in the bobbin opening, especially longitudinal. The end plugs prevent bend of the reed switch leads during mating and unmating of the leads and connectors; the holes 75 in the end plugs provide bearings for the reed switch shanks or leads, outboard and inboard, on each side of and very close to the bifurcated connectors 47 which effectively support the leads. The end plugs protect the reed switches and their leads and also the female connectors 47 from mechanical damage and external electrical shorting or grounding. They provide insulation between the plural connections of leads and connectors. The aligned apertures 67 and 59 between the end plugs and the bobbin end blocks 25 and 27 provide top access to the connectors for electrical test purposes.

Another advantage of the package is that no forming or termination of the reed switch shanks or leads 17 is required. Furthermore, the coil terminal lugs 33 present the same mating shape and comparable location as the reed switch leads so that the same female connector can be used for both leads and terminal lugs. The same package is used for both normally closed reed switches with permanent magnet bars and normally opened reed switches without permanent magnets, or a combination of twos is possible such as for example two normally closed and two normally opened. In view of the above, it is readily apparent that the present pluggable reed relay package is economical and suitable for mass production.

While the invention has been particularly shown and described with reference to preferred embodiments thereof, it will be understood by those skilled in the art that various changes in form and details may be made therein without departing from the spirit and scope of the invention. For example, the shape of the terminal lugs 33 may be modified and the lug may be arranged to be automatically inserted down from the top instead of in from the side as here disclosed. Furthermore, the T-slots 37, 39 may be reversed to extend down rather than up so that the bent-over flattened ends of the coil terminal lugs 33 are next to the card 49. The bobbin wire exit and entry slots used to route the coil ends to and from the terminal lugs 33 may be modified. The upstand-

ing bifurcated printed circuit board connector 47 may be varied such as by having a single slot 55 and revising the flared ends 53.

What is claimed is:

1. A pluggable reed relay comprising
a plurality of pairs of bifurcated connectors upstanding from a support and
a pluggable assembly removably mounted on said bifurcated connectors, said pluggable assembly comprising
a dry reed switch having a coaxial leads exterior to a sealing envelope; 5
a bobbin having a continuous axial opening and including a hollow hub and transverse end blocks, an end plug received in the opening of each of said end blocks, 10
said end blocks with said end plugs assembled therein having a plurality of pairs of aligned vertical bores therein, at least one of the pairs of vertical bores being in alignment with said hollow hub, 15
said end plugs also having aligned axial lead holes intersecting said one pair of vertical bores, 20
said reed switch being mounted within said bobbin between said end plugs with the leads thereof extending through said lead holes, each of said leads being supported by its respective end plug at either side of each of said one pair of vertical bores, 25
coil terminal means mounted in each of said end blocks and each including an axial contact extending across one of another pair of said vertical bores, and
said bifurcated connectors extending into said vertical bores in wedging engagement with said reed switch leads and coil terminal contacts to simultaneously establish electrical connection and mechanically lock said end plugs to said bobbin end blocks. 30
2. A pluggable reed relay comprising
a plurality of pairs of bifurcated connectors upstanding from a support and
a pluggable assembly removably mounted on said bifurcated connectors, said pluggable assembly comprising
a dry reed switch having coaxial leads exterior to a sealing envelope, 35
a bobbin having a continuous opening and including a hollow hub and elongated transverse end blocks, an end plug received in the opening of each of said end blocks, 40
the assembled end plugs and end blocks having a pair of aligned vertical bores which are also in axial alignment with said hollow hub, 45
said end plugs also having aligned axial lead holes intersecting said pair of vertical bores, 50
said reed switch being mounted within said bobbin between said end plugs with the leads thereof extending through said lead holes, each of said leads being supported by its respective end plug at spaced points 55
at either side of each of said pair of vertical bores, said end blocks having an additional pair of vertical bores, 60
coil terminal means mounted in each of said end blocks and each including an axial wire-like contact extending across one of said additional vertical bores, and
said bifurcated connectors extending into said vertical bores in wedging engagement with said reed switch leads and coil terminal contacts to simultaneously establish electrical connection and mechanically lock 65
said end plugs to said bobbin end blocks.
3. A pluggable reed relay comprising
at least two pairs of bifurcated connectors upstanding from a support and
a pluggable assembly removably mounted on said bifurcated connectors, said pluggable assembly comprising
at least one dry reed switch having coaxial leads exterior to a sealing envelope, 70
a bobbin including a hollow hub and transverse inte- 75

gral end blocks and having a continuous axial opening therethrough, an end plug slidably received in the opening in each of said end blocks, the assembled end plugs and end blocks having at least one pair of aligned vertical bores and said end blocks having at least one other pair of vertical bores, said end plugs also having aligned axial lead holes intersecting said first pair of vertical bores, said reed switch being mounted within said bobbin between said end plugs with the leads thereof extending through said lead holes, each of said leads being supported by its respective end plug at either side of said first pair of vertical bores, coil terminal means mounted in said end blocks and including axial contacts extending across each of said other pair of vertical bores, and an energizing coil wound around said hub with its ends secured to said terminal means, said bifurcated connectors extending into said vertical bores into wedging engagement with said reed switch leads and coil terminal contacts to establish electrical connection, one of said pairs of connectors having the dual function of mechanically locking said end plugs to said bobbin end blocks.

4. A pluggable reed relay assembly adapted to be removably mounted on pairs of bifurcated connectors upstanding from a support, said pluggable assembly comprising
at least one dry reed switch having coaxial leads exterior to a sealing envelope, 30
a bobbin having a continuous axial opening and including a hollow hub and transverse integral end blocks, an end plug slidably received in the opening in each of said end blocks, the assembled end plugs and end blocks having at least one pair of aligned vertical bores and said end blocks having at least one other pair of vertical bores, said end plugs also having aligned axial lead holes intersecting said first pair of vertical bores, said reed switch being mounted within said bobbin between said end plugs with the leads thereof extending through said lead holes, each of said leads being supported by its respective end plug at either side of said first pair of vertical bores, coil terminal means secured in said end blocks and having axial contacts extending across each of said other pair of vertical bores, and said pairs of bifurcated connectors being adapted to extend into said pairs of vertical bores into wedging engagement with said reed switch leads and coil terminal contacts to thereby establish electrical connection and simultaneously mechanically lock said end plugs to said bobbin end blocks.

5. A construction as defined in claim 4 for at least two normally closed reed switches, said end plugs further having at least one pair of aligned axial posts extending inwardly between adjacent pairs of said reed switches and cradling their respective sealing envelopes, and a permanent magnet bar retained between the opposing ends of said pair of posts each biasing a pair of the reed switches closed.

6. A pluggable reed relay assembly adapted to be removably mounted on pairs of bifurcated connectors upstanding from a support, said pluggable assembly comprising
at least two dry reed switches each having coaxial leads exterior to a sealing envelope, a bobbin having a continuous axial opening and including a hollow hub and elongated transverse integral end blocks, an end plug slidably received in the opening in each of said end blocks,

the assembled end plugs and end blocks each having at least two pairs of aligned vertical bores which are also in axial alignment with said hollow hub, said end plugs also having aligned axial lead holes intersecting each of said pairs of vertical bores and further having at least one pair of opposing posts extending inwardly within said hollow hub, said reed switches being mounted within said bobbin between said end plugs cradled against said posts with the leads thereof extending through said lead holes, each of said leads being supported by its respective end plug at either side of said pairs of vertical bores, 10
 said end blocks having two additional pairs of vertical bores at the extremities thereof, 15
 coil terminal lugs secured in the extremities of each of said end blocks and including axial wire-like contacts each extending across one of said additional vertical bores, and
 a pair of energizing coils wound on said hub with the ends thereof secured to said coil terminal lugs. 20
 7. A construction as defined in claim 6 further including a permanent bar magnet retained between each said pair of opposing end plug posts and the sealing envelopes of adjacent reed switches to bias the reed switches normally closed. 25

8. A pluggable reed relay comprising the combination of
 at least four pairs of bifurcated connectors upstanding from a support, and 30
 a pluggable assembly removably mounted on said bifurcated connectors, said pluggable assembly comprising
 at least two dry reed switches each having coaxial leads exterior to a sealing envelope, 35

a bobbin having a continuous axial opening and including a hollow hub and elongated transverse integral end blocks, 8
 an end plug slidably received in the opening in each of said end blocks, the assembled end plugs and end blocks each having at least two pairs of aligned vertical bores which are also in axial alignment with said hollow hub, said end plugs also having aligned axial lead holes intersecting each of said pairs of vertical bores and further having at least one pair of opposing posts extending inwardly within said hollow hub, said reed switches being mounted within said bobbin between said end plugs cradled against said posts with the leads thereof extending through said lead holes, each of said leads being supported by its respective end plug at spaced points at either side of said pairs of vertical bores, each of said end blocks having additional vertical bores at the extremities thereof, 15
 coil terminal lugs secured in the extremities of each of said end blocks and including axial wire-like contacts each extending across one of said additional vertical bores, and
 a pair of energizing coils wound on said hub with the ends thereof secured to said coil terminal lugs, said bifurcated connectors extending into said vertical bores into wedging engagement with said reed switch leads and said coil terminal contacts to establish electrical connection, inner pairs of said connectors having the dual function of locking said end plugs to said bobbin end blocks.
